CLAIM

The ornamental design for a ceiling fan light kit arm, as shown and described.

DESCRIPTION

FIG. 1 is a bottom perspective view of a ceiling fan light kit arm shown in the environment of a ceiling fan light kit with a light glass, showing my new design;

FIG. 2 is a top perspective view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a bottom perspective view of the ceiling fan light kit arm of FIG. 1, having the light glass of the ceiling fan light kit environment removed for clarity;

FIG. 9 is a top perspective view of the ceiling fan light kit arm of FIG. 2, having the light glass of the ceiling fan light kit environment removed for clarity;

FIG. 10 is a bottom view of the ceiling fan light kit arm of FIG. 3, having the light glass of the ceiling fan light kit environment removed for clarity;

FIG. 11 is a front view of the ceiling fan light kit arm of FIG. 4, having the light glass of the ceiling fan light kit environment removed for clarity;

FIG. 12 is a rear view of the ceiling fan light kit arm of FIG. 5, having the light glass of the ceiling fan light kit environment removed for clarity;

FIG. 13 is a right side view of the ceiling fan light kit arm of FIG. 6, having the light glass of the ceiling fan light kit environment removed for clarity; and,

FIG. 14 is a left side view of the ceiling fan light kit arm of FIG. 7, having the light glass of the ceiling fan light kit environment removed for clarity.

Portions of the ceiling fan light kit arm, the light glass, and the ceiling fan light kit environment shown in broken lines form no part of the claimed design.
